HEATER FOR INTERNAL-COMBUSTION ENGINES

Tracy W. Cox, Salem, Oreg., assignor to Cox Enterprises, Inc., Salem, Oreg., a corporation of Oregon

Application February 26, 1951, Serial No. 212,730

9 Claims. (Cl. 123—142.5)

1

This invention relates to a heater for use with an automobile engine or with any liquid cooled internal combustion engine to warm and to circulate the liquid engine coolant preparatory to starting the engine in cold weather.

During periods of cold weather, so-called "engine heaters" increasingly are becoming popular for use with emergency vehicles, trucks, and farm equipment. Additionally, many motorists in cold weather regions are beginning to appreciate the advantages of these devices as an aid to cold weather starting. In essence, the conventional engine heater comprises a hollow housing member having a waterproof heating element therein. A set of conduits are employed to connect this housing with the engine cooling jacket and with one of the radiator hoses. In addition, an electric cord is utilized to plug the heater element into an electric outlet of the type conventionally to be found in a garage or house lighting circuit. As the heater element begins to function, heat is transferred to the liquid engine coolant and a thermal circulation is set up through the cooling jacket and radiator. This heat and circulation warms the engine to facilitate starting and reduce engine wear normally incident to running a cold engine.

I have become interested in the manufacture of engine heaters and in the applications thereof to such emergency vehicles as police cars, ambulances, firetrucks, doctors' automobiles, repair vehicles, and the like. Such interest has led to a discovery of several disadvantages inherent in the conventional heater, which disadvantages it is an object of the instant invention to eliminate.

The prime disadvantages spring from the manner in which the conventional heater is joined to the engine cooling jacket and/or to one of the water hoses. Thus, the normal course of circulation through an automobile engine cooling jacket (after leaving the water pump) is from front to back along the lower or medial portion of the block, from back to front along the upper portion of the block, through the upper water hose, from top to bottom in the radiator, and back to the water pump through the lower water hose. Such a course, it will be noted, is in accord with the natural thermal currents in the jacket. When the conventional engine heater intake conduit is tapped into this course, either at the top of the block or at one of the water hoses, however, it gives birth to twin disadvantages.

The first such disadvantage is that the heater which is connected as above must circulate the liquid coolant through the radiator. This wastes

2

a large amount of heat and energy both by increasing materially the volume of liquid to be warmed and by requiring circulation through the radiator structure, which structure expressly is designed to dissipate heat. Accordingly, one object of my invention is to provide an engine heater which will by-pass the radiator and which need circulate the liquid coolant only through the jacket per se. One unexpected advantage flowing from the attainment of this object is that my engine heater warms only the coolant which first circulates through the hot water heater in the passenger compartment. Thus, my novel heater adds materially to the passenger comfort.

15 The second disadvantage to which I refer is that little, if any, of the warm liquid reaches the lower portion of the engine block after leaving the engine heater. This produces an uneven heating of the block and is a result to be avoided. 20 During the conduct of experimental tests, I have found that conventional heaters, after functioning for a period of time, will elevate the temperature of the coolant in the top of the jacket, yet will leave the bottom of the jacket cold. This condition results from the fact that the inlet conduit, from the jacket to the engine heater, conventionally is joined to one of the water hoses. These hoses draw their fluid supply from the upper portion of the jacket via the radiator or 25 from the upper portion of the jacket per se (depending upon the engine make and model). Within the scope of my invention, it is a prime object to change this conduit connection and location. Accordingly, my engine heater expressly 30 is pointed toward the attainment of uniform heating of the engine block, such as has been hitherto unattainable.

To attain the above listed objectives, I prefer to incorporate a Venturi structure in the inlet connection to the heater of my invention. The main flow of the venturi is derived from one of the water hoses or from the top of the jacket. The secondary flow, on the other hand, is derived from the lower portion of the jacket. Thus, the 35 thermal circulation through the venturi creates an area of low static pressure better to enhance the secondary flow from the lower jacket portion and better to achieve a uniform temperature throughout the engine block.

40 45 50 Further in accord with these objectives, my heater element is actuated by an adjustable thermostat in response to the engine temperature. This thermostat is preset to an actuation temperature approximately five degrees below the actuation temperature of the engine radiator thermo-

stat. Thus, the radiator, at all times, is closed to circulation and, in combination with my novel connection structure, no heat is wasted in warming the coolant in the radiator structure. This is in sharp contrast to the conventional engine heater.

These and other objects and advantages of my invention will be set forth in the following detailed description taken in conjunction with the accompanying drawing, wherein:

Fig. 1 is a side view of an automobile or other internal combustion engine showing my engine heater assembled and joined to the cooling jacket thereof in a manner uniformly to heat the entire engine block;

Fig. 2 is a detail view showing the distant controlled valve means selectively for closing and opening the return conduit leading to the top rear portion of the engine jacket;

Fig. 3 is a section detail view, taken substantially on the line 3—3 of Fig. 1, showing the adjustable thermostat control means which is responsive to the temperature of the engine to actuate the heater element of my invention; and

Fig. 4 is an enlarged detail view, partially in section, indicating the structure of the vertical housing member, heater element, and venturi.

I have chosen an L-type automobile engine 1, with which to illustrate the principles of my invention. Such a choice, however, is not intended as a limitation to the scope of my inventive concept since my engine heater is equally useful in conjunction with the valve-in-head and V-type automobile engines, with diesel engines, marine engines, and with a wide variety of liquid cooled internal combustion engines.

The engine illustrated comprises a radiator 2, a lower radiator hose 3, an upper radiator hose 4, an engine thermostat housing 4a, a by-pass radiator hose 5, and a water pump 5a. This structure, together with the cooling jacket which extends throughout the engine block, is conventional.

In Fig. 4, I have shown a cylindrical housing member 6 having a hollow chamber 7 open to a top outlet 8 and a bottom inlet 9. It is preferable, better to induce an efficient thermal circulation in the liquid engine coolant, that the cylindrical housing member 6 be mounted on the side of the engine 1 in a vertical position (see Fig. 1). This is because the natural direction of thermal circulation is from bottom to top. If desired, the vertical mounting may be accomplished by means of a strap hanger 10 and screws or rivets 11.

In the lower portion of the housing member 6, the screw threads 12 accommodate a fitting 13 which carries the heater element 14. Electric current is supplied to the heater element 14 through an electric cord 15 so the liquid engine coolant within the hollow chamber 7 will be warmed and a thermal circulation will be induced therein.

Referring more particularly to Figs. 1 and 3, an adjustable thermostat control means is shown mounted upon the engine 1 in a housing 16. Within this housing 16, the electric cord 15 and the electric cord 17 having the plug-in connection 18 are joined across a microswitch 19. A bimetallic element 20 spans the width of the housing 16 and is utilized to actuate the microswitch 19. Adjustment of the actuation temperature of the bimetallic element 20 is accomplished by means of a threaded shaft 21 having a knurled knob 22 and a pointer 23. The pointer

23 acts in conjunction with a dial scribed on the housing 16 (see Fig. 1) and indexed in degrees Fahrenheit. Thus, the bimetallic element 20 may be set to actuate the microswitch 19 at a temperature approximately five degrees lower than that temperature to which the automobile radiator thermostat 4a is set.

Returning to Fig. 4, I have shown a Y-fitting 24 having the leg thereof joined to the bottom inlet 9 and having the branches thereof joined to a first fluid conduit 25 and to a second fluid conduit 26, respectively. The second fluid conduit is shown provided with a terminal end 27. This end either may be a separate length of tubing, as shown, or may be an integral part of the conduit 26. In either event, the terminal end 27 protrudes into the first fluid conduit 25 adjacent the junction of the Y-fitting 24. This protrusion restricts the cross-sectional area of the conduit 25 adjacent the Y junction thereby to define a Venturi means. Due to this restricted cross section, the velocity of flow into the chamber 7 is increased and the static pressure is decreased. This reduction in static pressure enhances the flow of liquid coolant through the second fluid conduit 26 and is of particular importance to my inventive concept. One reason for this importance is that prior art devices have failed to produce sufficient coolant flow down through the restrictive passages provided around the cylinders and in the lower portion of the engine block.

After the liquid coolant is warmed in the chamber 7 by the heater element 14, thermal circulation causes the liquid to rise through the chamber, out the top outlet 8, and through the return conduit 29. This return conduit 29 is joined to the upper rear portion of the cooling jacket as shown in Fig. 1. If the engine 1 is located in an automobile or truck having a hot water heater in the passenger compartment thereof, I prefer to employ a T-fitting 30 having a distant controlled valve 31 to join the return conduit 29 to the engine block. This is for the reason that the hot water heater intake pipe 32 should be closed off while my engine heater is functioning else a great deal of heat energy will be wasted in circulation through the hot water heater structure. To this end, it will be noted that the valve 31 may define one of two positions. In the first position (see Fig. 2), the return conduit 29 is open to the top of the jacket and the car heater intake pipe 32 is closed. In the second position, the conduit 29 is closed and the pipe 32 is open to allow the car heater to function normally. Actuation of the valve 31 is provided by means of a distant control knob 33 which may be mounted on the dash and which acts through a pivot link 34. Thus, when the truck or automobile is to be driven, the driver may control the position of the valve 31 from inside the cab or automobile passenger compartment. Furthermore, the valve 31 allows the coolant to be warmed prior to the time the hot water heater is used. Heat is thus made available to the passenger compartment as soon as the valve 31 is actuated.

Turning now to the operation of my engine heater, it will be noted that the second fluid conduit 26 is joined to the lower portion of the engine cooling jacket, as by a connection 35, and the first fluid conduit 25 is joined to the lower radiator hose 3. Since the hose 3, in turn, is joined to the upper portion of the jacket, the first fluid conduit 25 will draw liquid coolant

from this portion of the jacket. During periods of cold weather and while the engine 1 is not in use, the plug-in connection 18 is joined to an electric outlet of the type conventionally to be found in a garage or house lighting circuit. In addition, the knurled knob 22 is adjusted to set the actuation temperature of the bimetallic element 20 and the microswitch 19 approximately five degrees below the actuation temperature of the radiator thermostat 4a. In practice, I have found that this setting will vary between a maximum of 185 degrees Fahrenheit and a minimum of 100 degrees Fahrenheit, depending upon the make and type of engine.

With the adjustable thermostat control means set, the heater element 14 alternately will be turned on and shut off in response to the engine temperature. Furthermore, the heater element 14 will warm the liquid engine coolant and induce a thermal circulation therein sufficient to pump the coolant throughout the cooling jacket and through the various conduits and pipes. During a typical cyclic operation, the warmed coolant rises within the chamber 7, passes through the return conduit 29 and T-fitting 30 into the upper rear portion of the jacket. From this point the warmed liquid circulates forward and downward through the jacket. Since the passages through the upper portions of the jacket are relatively large, a major portion of the coolant will circulate along the top of the jacket, through the by-pass radiator hose 5 (because the thermostat 4a is closed), past the water pump 5a, down the lower radiator hose 3, and through the first fluid conduit 25 into the Y-fitting 24. Within the Y-fitting 24, a Venturi effect is established and an area of low static pressure is produced about the terminal end 27 of the second fluid conduit 26. This area of low static pressure enhances the flow through the second fluid conduit 26 to drain a portion of the coolant from the restricted passages in the lower portion of the jacket. Thus, a continuous thermal circulation and flow takes place evenly throughout the entire engine cooling jacket. Such a continuous, uniform circulation achieves a uniform, preset temperature throughout the engine block in satisfaction of one of the prime objects of my invention.

Further in accord with the objects of my invention, it will be noted that the adjustable thermostat control means never allows the liquid coolant temperature to rise to a point where the radiator thermostat 4a will be opened. Accordingly, the radiator 2, at all times, is closed to circulation. It is this novel control means for the heater element 14, taken in conjunction with my novel connection structure, which eliminates entirely the waste of heat energy afforded by the conventional engine heater in warming the radiator contained portion of the coolant and in warming the radiator structure. As can be seen, the provision of an engine heater which will by-pass the radiator and which need circulate the liquid coolant only through the cooling jacket per se is in direct service of the objects of my invention.

I claim:

1. A device for heating the liquid coolant carried in the cooling jacket of an engine, comprising a housing member having a hollow chamber communicating with the upper rear portion of said jacket and with a fluid conduit, respectively, said fluid conduit having means simultaneously for conveying said liquid coolant both from the top and the bottom of said jacket to said chamber to promote uniform heating of the engine, and means carried by said chamber to induce circulation through the jacket and conduits.

2. A device for heating the liquid coolant carried in the cooling jacket of an engine, comprising a housing member having a hollow chamber communicating with the upper rear portion of said jacket and with a fluid conduit, respectively, said fluid conduit having means for conveying said liquid coolant from the bottom of said jacket to said chamber to promote uniform heating of the engine, and heater means carried by said chamber to warm said liquid coolant and induce circulation through the jacket and conduits, said heater means being actuated by control means responsive to the temperature of said engine.

3. A device for heating the liquid coolant carried in the thermostat controlled cooling jacket of an engine, comprising a vertical housing member having a hollow chamber communicating at the upper end thereof with the upper rear portion of said jacket and at the lower end thereof with a fluid conduit, respectively, said fluid conduit having means simultaneously for conveying said liquid coolant both from the top and the bottom of said jacket to said chamber to promote uniform heating of the engine, and means carried by said chamber to induce thermal circulation through the jacket and conduits, said latter means being actuated by control means responsive to the temperature of said engine and preset to a temperature less than the actuation temperature of the thermostat control in said cooling jacket.

4. A hollow chambered housing member having a heater means for warming the liquid coolant which is carried in the cooling jacket of an internal combustion engine, comprising a first fluid conduit joining the upper front portion of said jacket to said chamber and a second fluid conduit joining the lower portion of said jacket to said first conduit, the terminal end of said second conduit protruding into said first conduit to define therewith a Venturi means for lowering the static pressure at said terminal end to enhance fluid flow from the lower portion of said jacket, and a return fluid conduit joining said chamber to the upper rear portion of said jacket.

5. In combination with the cooling jacket of a liquid cooled internal combustion engine, a vertical housing member having a hollow chamber therein, heater means within said chamber for warming and for inducing thermal circulation of the liquid engine coolant, a first fluid conduit joining the upper front portion of said jacket to the bottom of said chamber and a second fluid conduit joining the lower portion of said jacket to said first conduit, the terminal end of said second conduit protruding into said first conduit to define therewith a Venturi means for lowering the static pressure at said terminal end, a return fluid conduit joining the top of said chamber to the upper rear portion of said jacket, and control means responsive to the engine temperature to actuate said heater means.

6. In combination with the cooling jacket of a liquid cooled internal combustion engine, a vertical housing member having a hollow chamber therein open to a top outlet and a bottom inlet connection, heater means within said chamber for warming the liquid engine coolant and including thermal circulation therein, a Y-fitting having the leg thereof joined to said inlet and having the branches thereof joined to a first and to a second fluid conduit, respectively, said first con-

duit being joined to the upper front portion of said jacket and said second conduit being joined to the lower portion of said jacket, a return fluid conduit joining said outlet to the upper rear portion of said jacket, and control means responsive to the engine temperature to actuate said heater means, said control means including an adjustable thermostat mounted upon said engine.

7. In combination with the cooling jacket of a liquid cooled internal combustion engine, a vertical housing member having a hollow chamber therein open to a top outlet and a bottom inlet connection, heater means within said chamber for warming the liquid engine coolant and inducing thermal circulation therein, a Y-fitting having the leg thereof joined to said inlet and having the branches thereof joined to a first and to a second fluid conduit, respectively, said first conduit being joined to the upper front portion of said jacket and said second conduit being looped about said engine and joined to the lower medial portion of said jacket, a return fluid conduit joining said outlet to the upper rear portion of said jacket, said return conduit carrying distant controlled valve means selectively for closing and opening the same to fluid flow, and control means responsive to the engine temperature to actuate said heater means, said control means including an adjustable thermostat mounted upon said engine.

8. In combination with the cooling jacket of a liquid cooled internal combustion engine, a vertical housing member having a hollow chamber therein open to a top outlet and a bottom inlet connection, heater means within said chamber for warming the liquid engine coolant and inducing thermal circulation therein, a Y-fitting having the leg thereof joined to said inlet and having the branches thereof joined to a first and to a second fluid conduit, respectively, said first conduit being joined to the upper front portion of said jacket and said second conduit being joined

to the lower portion of said jacket, said second conduit including Venturi means for enhancing fluid flow from said jacket lower portion, and a return fluid conduit joining said outlet to the upper rear portion of said jacket.

- 5 9. In combination with the thermostat and cooling jacket of a liquid cooled internal combustion engine, a vertical cylindrical housing member mounted adjacent the side of said engine and having a hollow chamber therein open to a top outlet and a bottom inlet connection, heater means within said chamber for warming the liquid engine coolant and inducing thermal circulation therein, a Y-fitting having the leg thereof joined to said inlet and having the branches thereof joined to a first and to a second fluid conduit, respectively, said first conduit being joined to the upper front portion of said jacket and said second conduit being joined to the lower portion of said jacket, said second conduit including Venturi means protruding into said first conduit adjacent the junction of said Y-fitting for enhancing fluid flow from said jacket lower portion by lowering the static pressure at said junction, a return fluid conduit joining said outlet to the upper rear portion of said jacket, and control means responsive to the engine temperature to actuate said heater means, said control means being preset to a temperature less than 20 the actuation temperature of the engine thermostat.
